Primary Examiner—George P. Word

Attorney, Agent, or Firm—Stetina and Brunda

[57] CLAIM

The ornamental design for a combined chuck key holder and cord restraint, as shown and described.

DESCRIPTION

FIG. 1 is a top perspective view of a combined chuck key holder and cord restraint showing my new design; and

FIG. 2 is a bottom perspective view thereof.
The environmental structure shown in dotted lines in FIGS. 1 and 2 is for illustrative purposes only and not a part of the claimed design.
